UNITED STATES PATENT OFFICE.

CHARLEY McDONNER, OF WAUSAUKEE, WISCONSIN.

SHADE AND CURTAIN-POLE HOLDER.

SPECIFICATION forming part of Letters Patent No. 734,131, dated July 21, 1903.

Application filed February 13, 1903. Serial No. 143,200. (No model.)

To all whom it may concern:

Be it known that I, CHARLEY McDONNER, a citizen of the United States, residing at Wausauke, in the county of Marinette and 5 State of Wisconsin, have invented a new and useful Shade and Curtain-Pole Holder, of which the following is a specification.

This invention relates particularly to improvements in supports for roller window-curtains, curtain-poles, and the like.

It is the object to provide a structure of this character that can be readily applied to a window-frame by an inexperienced person without the use of tools and without injuring 15 or marring the frame. It is readily adjustable to different sizes of windows, is secure and rigid when in place, is very simple in construction, and consequently can be manufactured at small cost.

20 The preferred embodiment of the invention is illustrated in the accompanying drawings, wherein—

Figure 1 is a perspective view of the improved holder, and Fig. 2 is a sectional view 25 through the same.

Similar reference-numerals indicate corresponding parts in all the figures of the drawings.

In the embodiment herewith illustrated a 30 pair of slidably-associated overlapped supporting members are employed, which are in the form of rods 10. The outer ends of these rods are split, as shown at 11, and the fingers 12 thus formed are spread apart, and to their 35 free ends are secured hanger members in the form of brackets 13. These brackets are preferably ornamental in form, having seats 14 for the reception of the usual pintles or gudgeons of the ordinary roller-shade and being also provided with outstanding hooks 15, 40 that constitute the pole-engaging means.

Securing means in the form of a clamp 16 is attached to the inner end of each rod 10. These clamps are substantially duplicates 45 and comprise upright bars having rearwardly-extending lugs 17, through which are threaded oppositely-disposed set-screws 18. The clamps are also provided with outstanding ears 19, one of the supporting-rods being attached to each ear and slidably passed through 50 an opening 20 of the other. The clamps are

located between the hanger members or brackets, as shown.

In applying the improved holder to a window the clamps are arranged with the lugs 55 embracing the upper frame-piece, as illustrated in Fig. 2, and said clamps are moved toward or from each other to bring the hanger-brackets in proper position with relation to the sides of the window. When this position has been reached, the set-screws 18 are tightened, thus clamping the entire structure rigidly to the window-frame and at the same time securing the sections against relative movement. It will be apparent that an inexperienced person can apply this structure and that it may be readily elongated or contracted to the size of the window. The parts are simple and can be easily manufactured, and, furthermore, they do not mar the window-frame to any appreciable extent.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 80 of the invention.

Having thus fully described my invention, what I claim as new, and desire to secure by Letters Patent, is—

1. In a holder of the class described, the 85 combination with overlapped slidably-associated supporting members, of a hanger member carried by the outer end of each supporting member, and separate securing devices attached to the inner ends of the supporting 90 members and movable toward and from each other.

2. In a holder of the class described, the combination with overlapped slidably-associated supporting members, of a securing device attached to the inner end of each supporting member and slidably associated with the other member, and a hanger-bracket attached to the outer end of each supporting member.

3. In a holder of the class described, the combination with slidably-associated support-

ing members, of a hanger-bracket attached to the outer end of each supporting member, and a securing device fastened to the inner end of each supporting member and designed 5 for attachment to a window-frame, said securing devices being located between the hanger-brackets.

4. In a holder of the class described, the combination with frame-engaging clamps, of 10 supporting-rods, each being attached to one clamp and slidably engaging the other, and a hanger-bracket secured to the outer end of each rod outside the clamps.

5. In a holder of the class described, the 15 combination with frame-engaging clamps having offset lugs arranged to embrace the upper bar of a window-frame, said lugs being provided with set-screws, the clamps also having outstanding ears, of supporting-rods, each

being attached at the inner end to the ear of 20 one clamp and slidably engaging the ear of the other clamp, the outer ends of the rods being split, and a hanger-bracket secured to the outer split end of each rod.

6. In a holder of the class described, the 25 combination with overlapped supporting members, of a separate securing member carried by each supporting member and having a sliding engagement with the other supporting member, and hanger devices carried 30 by the supporting members.

In testimony that I claim the foregoing as my own I have hereto affixed my signature in the presence of two witnesses.

CHARLEY McDONNER.
